DESIGN FOR A SLIP

Sol Friedman, New York, N. Y.

Application November 7, 1941, Serial No. 104,082

Term of patent 3½ years

To all whom it may concern:

Be it known that I, Sol Friedman, a citizen of the United States and resident of the Borough of Manhattan, in the city, county, and State of New York, have invented a new, original, and ornamental Design for a Slip, of which the following is a specification, reference being had to the accompanying drawing, forming part thereof,

Fig. 1 is a front view of a slip embodying my new design.

Fig. 2 is a rear view of the same.

I claim:

The ornamental design for a slip, substantially as shown,

SOL FRIEDMAN,
